UNITED STATES PATENT OFFICE.

FREDERICK G. MANLY, OF CHICAGO, ILLINOIS.

SPRAY-NOZZLE.

1,033,603.

Specification of Letters Patent.

Patented July 23, 1912.

Application filed February 12, 1912. Serial No. 677,138.

To all whom it may concern:

Be it known that I, FREDERICK G. MANLY, a citizen of the United States, residing at Chicago, in the county of Cook and State of Illinois, have invented certain new and useful Improvements in Spray-Nozzles, of which the following is a specification.

The device of the present invention relates to a nozzle adapted to break a stream of fluid passed therethrough into spray for the purpose of distributing said fluid in the form of fine particles over a relatively large area.

The objects of the present invention are to produce a nozzle for accomplishing the above result which is cheap and simple as well as strong and durable of construction, and which will so deflect and break up the streams of fluid as to produce a sheet of spray which will cover all the surface intended; that is to say, the spray when projected will be in such form that upon striking the surface upon which it is to be deposited it will entirely cover said surface. It will not simply fall upon the edges of said surface, but will cover the entire surface, thereby obviously increasing the effectiveness of the spray.

Further objects of the invention are to produce a nozzle which can be easily kept clean; which will be capable of operation under varying degrees of pressure; and which can be used under conditions where heat is present without danger of becoming cracked or otherwise mutilated by the expansion and contraction which necessarily takes place in devices subject to unusual heat influences.

The invention further consists in the features of construction and in the combination of parts hereinafter described and claimed.

In the drawings, Figure 1 is a view, partly in section, showing the spraying appliance of the present invention in operative position; Fig. 2, a vertical section of the spraying appliance; Fig. 3, a section taken on line 3-3 of Fig. 2, looking in the direction of the arrow; and Fig. 4, a section on line 4-4 of Fig. 2, looking in the direction of the arrow.

For the purpose of illustrating one application of my invention, I have illustrated it in connection with an oil receptacle 5 of a type used in conjunction with the carbureter of a gas furnace. However, it is not the intention

to in any wise limit the use of the spray to this particular mechanism, although it possesses certain structural features which especially adapt it for usage with such a mechanism. It may, however, be readily used in other fields without departing from the spirit of the invention. The receptacle 5 is provided with a screw-threaded upper opening 6, into which is entered a supply pipe (not shown) for conducting liquid to the receptacle; and said receptacle, at its lower end, is provided with an interiorly screw-threaded surface 7, but the present invention, as previously stated, is not at all limited to a usage in connection with such a form of receptacle.

The spraying nozzle of the present invention consists of a body portion 8, comprising an upper or head-like portion 9, and a lower or flange-like portion 10. The flange-like portion may be configured, as clearly shown in Figs. 1, 3 and 4, to form a nut to which a tool can be applied for the purpose of fastening or loosening the spraying nozzle from the device to which it is attached. The head-like portion 8 terminates in an offset portion 11, as shown in Fig. 2, and the nozzle in the form shown may be said to be of stepped formation in cross-section from its upper to its lower end, said offset portion being provided with screw-threads adapted to engage the screw-threads on the surface 7. And the body portion is provided with a centrally located discharge opening 12, which, in the form illustrated, is of a conical formation. An upper or inner series of ducts or passages 13, and a lower or outer series of ducts or passages 14 lead into this central discharge opening 12. The upper series of ducts 13 is more clearly illustrated in Fig. 3, and, as will be seen from a study of this figure, said ducts are arranged in radial alinement with the center of the opening 12. By this arrangement, the streams of liquid forced through these ducts or passages 13 and discharged into the central opening 12 will collide or impact with one another at a point approximately the center of the opening 12; and by such collision or impact these streams will be broken into spray, which will fall downwardly and be discharged through the center of the opening 12.

The ducts or passages 14 are more clearly illustrated in Fig. 4, and, as will be seen from Fig. 2, the ducts or passages 13 are

arranged to permit the fluid to enter these passages at a point above the offset 11, whereas the lower openings 14 extend through this offset portion, and in order to 5 permit the fluid to enter these passages 14, cross passages 15 are provided, extending transversely through the offset portion 11 and communicating with the ducts or passages 14. Referring again to Fig. 4, it will 10 be seen that the ducts 14 are arranged out of radial alinement with the center of the opening 12, and they are so arranged with respect to one another as to give a whirling movement to the streams of liquid passing 15 therefrom into the opening 12; that is, they direct the streams toward the sides of the opening rather than toward the center, and the streams are thus deflected so as to follow the walls of said opening. These walls being 20 of circular formation, said streams will naturally be given a whirling or rotative movement, which will break them into spray and tend to force or throw them outwardly from the center of the opening 12, so that 25 when finally discharged from said opening, they will be in the form of a circle.

As heretofore explained, the liquid coming through the openings 13 will be discharged downwardly at the center of the 30 opening 12, and the liquid coming through the openings 14 will be discharged around the walls of the opening 12. In this manner the two streams of liquid when broken into spray will produce a mass of spray of 35 circular formation. Obviously, if the openings 14 alone were utilized, the spray discharged would be in the form of a hollow ring. If the openings 13 alone were utilized, the spray discharged would be in the form 40 of a relatively small circle. By utilizing the two sets of openings in conjunction with one another, the discharge from the openings 14 form the outline of a discharged mass of spray, while the discharge from the openings 13 fill in the interior thereof, thus 45 effecting the discharge of a complete and unbroken mass of spray.

By referring to the drawings, it will be noted that all of the openings or conduits 50 are of a nature whereby they may be easily cleaned and can be made of sufficient diameter so that the danger of their becoming choked is avoided; and, furthermore, the movements given to the streams of liquid 55 are sufficient to break them into spray even though the pressure upon the liquid may be comparatively light.

As heretofore stated, the present invention is particularly designed and adapted 60 for use in connection with carbureters used upon gas furnaces, and when employed for such usage the formation is particularly adapted to withstand, without material damage, the expansion and contraction 65 which naturally take place. It will be

noted that the head 8 is of a substantially thick and solid nature. Hence this head will, for a considerable period of time, remain in a relatively cool condition, and the oil striking this head and flowing over it 70 will become more or less cooled, so that upon reaching the offset 11, it will not be in such a heated condition as to cause a sudden expansion of the metal at this point and consequently a breakage. 75

The device may be easily removed to permit of the substitution of a different form of spray, if desired; and by changing the configuration of the central opening 12, the figure described by the projected spray can 80 be varied, so as to allow the projected spray to cover a restricted or wide area, as desired.

In Fig. 1, I have illustrated a strainer 16, which may be employed with the device if desired, such an application being especially desirable in case the liquid being 85 treated is of a muddy or dirty nature.

I claim:

1. A spray nozzle, comprising a body portion having a discharge opening therein, a series of inner passages and a series of outer passages extending through the body portion and communicating with said discharge opening, said inner passages being arranged in radial alinement with said opening, and said outer passages being arranged out of radial alinement with said opening, substantially as described. 90

2. A spray nozzle, comprising a body portion having a conical discharge opening 100 therein, a series of inner passages and a series of outer passages extending through the body portion and communicating with said discharge opening, said inner passages being arranged in radial alinement with 105 said opening, and said outer passages being arranged out of radial alinement with said opening, substantially as described.

3. A spray nozzle, comprising a body portion terminating in an offset, said body portion being provided with a central discharge opening, a series of inner passages and a series of outer passages extending through the body portion and communicating with said discharge opening, said inner passages opening above said offset portion, said outer passages extending through said offset portion, said inner passages being arranged in radial alinement with the center of said discharge opening, said outer 110 passages being arranged out of radial alinement with said discharge opening and in oblique relation to said upper passages, and a series of by-passes extending transversely through the offset portion and communicating with the lower set of passages, substantially as described. 115

4. A spray nozzle, comprising a body portion terminating in an offset, said body portion being provided with a central coni- 120

cal discharge opening, a series of inner passages and a series of outer passages extending through the body portion and communicating with said discharge opening, said 5 inner passages opening above said offset portion, said outer passages extending through said offset portion, said inner passages being arranged in radial alinement with the center of said discharge opening, 10 said outer passages being arranged out of radial alinement with said discharge opening and in oblique relation to said inner passages, and a series of by-passes extending transversely through the offset portion 15 and communicating with the outer set of passages, substantially as described.

5. A spray nozzle, comprising a body portion provided with a central discharge opening, means for directing streams of 20 liquid into said discharge opening in lines radial to the center of said opening, and means for directing streams of liquid into said discharge opening beyond the first mentioned streams and in lines out of radial alinement with said discharge opening, 25 substantially as described.

6. A spray nozzle, comprising a body portion having a discharge opening therein, means for directing streams of liquid into said opening to bring them into impact with one another at the center of said opening, and means for directing streams of liquid into said opening beyond said first mentioned streams and in lines whereby they are directed toward the sides of said 35 opening, substantially as described.

7. In a spraying appliance, the combination of a body portion embodying a relatively thick head, a discharge opening extending into said body portion, means for 40 directing streams of liquid into the inner part of said discharge opening, whereby they collide at the center of said opening, and means for directing streams of liquid into said discharge opening beyond the first 45 mentioned streams, the latter streams being directed toward the side walls of said discharge opening, substantially as described.
